UNITED STATES PATENT OFFICE.

WILL K. MONROE, OF CLEVELAND, OHIO, ASSIGNOR TO THE BROWN HOISTING MACHINERY COMPANY, OF CLEVELAND, OHIO.

APPARATUS FOR SCREENING COAL.

1,023,582.

Specification of Letters Patent.

Patented Apr. 16, 1912.

Application filed February 4, 1911. Serial No. 606,628.

To all whom it may concern:

Be it known that I, WILL K. MONROE, a citizen of the United States, residing at Cleveland, in the county of Cuyahoga and State of Ohio, have invented a new and useful Apparatus for Screening Coal, of which the following is a full, clear, and exact description, wherein reference is made to various parts, shown in the drawings accompanying this application, by the same letter or numeral in each instance.

The improvement relates to and is designed more especially for screening bituminous coal at docks, yards and similar points or places from which it is to be later transhipped in the several sizes or grades required for traffic, manufacturing, and domestic uses. These sizes or grades have each a relative demand, and market designation or trade name, respectively, of "lump," "stove," "nut" and "screenings," and, at present are derived from run-of-the-mine or pile lots by elevating these masses or lots to given heights one or more times according to the sizes to be separated, and then precipitating the same downwardly upon screens whose meshes, at each precipitation, are of requisite dimensions to hold out the larger sized coal in the mass, and allow the smaller sizes to pass through to the pit or general storage place below. From here they will be again raised and precipitated as occasion demands.

Existing methods include few, if any, facilities for breaking or modifying the fall of the material to said pit; and the angles of the various declivities involved are mainly determined with regard to the points of delivery or screening conditions only rather than with respect to their value or bearing upon the coal disintegration that is to occur. In these methods, therefore, besides the loss occasioned by reason of the number and character of the operations themselves, the loss on account of the breakage and degradation of the coal during the process, is so enormous as to make it of great importance that the entire process be simplified to the end, especially, that the re-handling of the coal feature shall be minimized and moderated to the fullest degree possible.

It is the object of the present invention to so reorganize, improve upon and add to the essential features of coal screening systems generally, as to supply a special form of

mechanism and resultant combination, that shall go far toward meeting and overcoming the serious deficiencies, in the class of apparatus in question, to which allusion has already been made. I accomplish this object by the peculiar collocation and structural combination of screens, elevators, conveyors, chutes and subordinate parts that I shall now proceed to more particularly explain.

In the drawings, Figure 1 is a side view of the apparatus proper, Fig. 2, an end view of the same in the direction of the arrow in Fig. 1, and, Fig. 3 is a side view of a similar apparatus in connection with an overhead bridge tramway for handling the coal to be screened.

The apparatus as shown, comprises a rigid portal supporting framework that spans two railroad tracks, represented as having cars W and X thereon, ready to receive their loads. The framework includes four corner posts or legs, three of which, marked P and P', appear in the drawings. The posts or legs themselves are each mounted upon four-wheeled trucks T T adapted to travel upon rails r r that lead to the several points or locations where the apparatus is to be used. Suspended within said framework, from parallel girder-members therein G, G' and G², are three bins B, B' and B². The bins B and B' are of the parabolic suspension shape with vertical ends, and B² is of the same shape but in both directions. The bins, as well as the compartments in B, each have a capacity of perhaps fifty net tons.

The bin B² is the receiving bin into which run-of-the-mine coal, for instance, is primarily deposited for screening. It is at right angles to B and B' which are located in line with each other. The bin B is subdivided into three compartments or subordinate bins 1, 2 and 3, by transverse partitions indicated by the dotted lines b and b' in Fig. 1, and, at or near the lower part of each of these compartments is arranged on parallel lines, a pair of right and left spouts denoted, respectively, by S S', S² S³ and S⁴ S⁵. Said spouts are provided at their outer ends with movable sections s, s', s², s³, and s⁴, s⁵, with chain hoists or other suitable means, h and h' for raising and lowering the same and thereby regulating or closing said spouts.

A spout S⁶, similar to and in line with

the spouts S , S^2 , and S^4 just described, is provided at or near the lower part of the bin B' , but in place of a companion spout for the same corresponding with S' , S^3 or 5 S^5 , there is located, on the opposite side of B' , a downwardly extending chute C (Fig. 2) that empties into a boot or screening receptacle below. This boot O is itself firmly suspended within the framework of the apparatus, immediately below a rectangular shaker-screen H , to be further described. Its upper end or mouth corresponds in outline and relative location with the contour of the screen H which it serves, and its 10 lower or discharge end is connected with and opens into an elevator A at its foot.

The third bin B^2 is hung from parallel girders G^2 and G^2 at the right of the two bins already described. It is extended 20 downwardly at varying angles by means of a chute D' which joins and terminates in the boot O near the point where the latter opens into said elevator. The flow of the contents from the bins B' and B^2 and from 25 the boot O , may be governed by slide-gates g' and g^2 , respectively, at the several points of junction of the chutes with the bins, and, by a gate g^3 at the lower or discharge end of O . It will be found of advantage, however, 30 and in line with the general structural scheme of the apparatus, to have these or similar gates at the discharge ends of both C and D' , inasmuch as, after the chutes have once been filled a continuous, instead of an 35 abrupt fall or flow of the material outward from these receptacles will thereby be assured. A short spout D further extends from the lower part of B^2 to a point directly about the inclined rectangular screen H 40 above referred to. Said screen, when in place, is suitably supported in a frame to be oscillated forward and back in guides therein by means, for instance, of eccentrics, attached to a shaft c , driven by an electric 45 motor indicated by M .

The screen itself will be one of a set of screens adapted to screen and separate the various sizes of coal desired, and be interchangeable on said guides, with the other 50 members of the set as occasion requires.

The screen is intermittently fed from the bin B^2 above, through a sliding gate F by means of suitable oscillating connections between the gate and the motor M as indicated 55 by c' ; its lower or discharge end, is arranged to deliver the coal that passes down the screen into a small hopper R , immediately below which, in turn, feeds on to an apron or belt conveyer V^2 that is pivoted to 60 the framework, just beneath said hopper, at p . The conveyer is provided with means for being raised and lowered about its pivot, indicated by h^2 and h^3 , and its discharge end is shown as equipped with sectional extension chutes t and t' to further facilitate the 65

delivery of the coal in the cars beneath. The conveyer is actuated by a special motor M^2 .

Extending lengthwise beneath the spout sections s , s^2 , s^4 and s^6 , and, in close proximity to the same, is a belt conveyer V having a discharge chute K therefor, at the front end, leading outwardly from the structure, and, a similar chute K' at the rear end, that leads inwardly of the same toward the position where a car is to receive its load beneath; the latter chute is preferably provided with an extension apron denoted by t^2 , that may be raised or lowered to regulate the fall. A second belt conveyer V' 75 likewise extends beneath the spout sections s' , s^3 and s^5 , parallel with V , with its rear terminal discharging into the chute K' , and its front terminal onto an inclined lip-screen H' . Said belt-conveyers are adapted 80 to travel in either direction, alternatively, and are driven by a special motor M' .

The screen H' like H , is interchangeable, with screens of different mesh dimensions and discharges the coal that passes over 90 the same, into the hopper R , and the coal that passes through the same, into a pan or box O' beneath the same that empties into the chute C .

A is an upright bucket elevator of any 95 suitable formation, situated intermediately of said re-sizing bins B and B' . Its foot or lower terminal unites and coalesces with the boot O at its lowest part so as to take its loads and be fed therefrom. The upper 100 terminal of the elevator is immediately above said bins where it discharges its loads upon a deflecting butter-fly valve N , into one or the other of the oppositely located lateral chutes or spouts L and L' , according to the direction of said valve.

The chute L' empties into the bin B' , and the chute L , into a cylindrical rotatory screen U , that is operatively inclined above the several compartments 1, 2 and 3 of the 110 bin B .

U is a graduated screen, of the single shell type, in two screen sections u and u' , arranged in the reverse order of their mesh dimensions, above the compartments 3 and 115 2 respectively, and a lower blank section u^2 that empties into compartment 1. These screen sections must conform in length with the compartments they serve. By the arrangements just described "final screenings" only will be separated from the mass and fall through the section u into the compartment 3, "nut" only will be screened through u' into compartment 2, and the residuum of the loads, after the "final screenings" and nut have thus been screened from the same, as "stove," will run down over the blank section u^2 , into the compartment marked 1.

The necessary rotation of the screen U , 130

is effected by revolving the wheel bearings f , f' on which it rests, through the common shaft f'' by motor and gear connection to be provided for the purpose, that are here indicated by M^3 . A motor M^4 properly connected with suitable driving mechanism to actuate the elevator A is indicated at the foot of the elevator in dotted lines.

W and X are, respectively, a hopper and box car, in position to be loaded by the apparatus. In the latter of the cars a box-car loader Y, and its exteriorly located controller y , is indicated in dotted lines.

I is the operator's house, and Z the general screenings storage or overflow pile.

In Fig. 3 the apparatus is shown in a fixed and operative relation with a bridge-tramway J whose legs J' J' are affixed to and straddle the portion of the frame-work 20 of the apparatus that carries the bin B², and, together, with said screening device composes a complete unitary coal-handling plant.

The shipping and assorting conditions 25 which the apparatus is adapted to meet and serve, are many and varied. A run-of-the-pile, or a "general screenings" shipment can always be made by simply dumping the lot to be shipped, into the primary bin B² 30 by a bridge tramway, locomotive cranes or other means, and then running it out, through the short spout D, over a blank (by which the screen H has been replaced) onto the conveyer V² to the car. If lump coal 35 is to be shipped from the run-of-the-pile, for instance, and the bin B is empty, the bin B² is filled, as before, a suitable sizing screen inserted at H, and the motor M started that oscillates the screen and the sliding gate F, as well as the motors M³ and M⁴ 40 that actuate the elevator A and screen U. The lump will thereupon run down the screen H to the car, as described, and the balance of the discharge pass through said screen as "general screenings" into the boot O 45 from whence it will be carried up and discharged through the spout L into U, the valve N having been properly deflected for the purpose. The general screenings will 50 now be deposited into the compartments 1, 2 and 3, according to its constituent sizes of "stove," "nut" and "final screenings," until either the lump shipment is finished, or the compartments are filled. The latter 55 condition occurring, the valve N is reversed, the rotation of U stopped, and the flow of "general screenings" turned into the reserve bin B'. If the bin B' or any of the compartments of B is or becomes filled during 60 the lump shipment, room may be made therein for the continued flow of its grade, by lowering its spout s', s³, s⁵ or s⁶ and carrying off what would otherwise be overflow by means of the belt conveyer V to either 65 the car W through the spout K', or, in the

opposite direction, through the spout K to the pile Z. If, however, any one of the sizes in bins B and B' are to be loaded into a car W, at the same time as the car X is being loaded with lump, the operation first described, will be varied by lowering the proper spout in the compartment of the size selected, so that such size shall flow off as fast as it flows in. This overflow may be carried by V', toward a car W or X and any 70 overflow, in the meantime, of the other receptacles fed by the elevator A, may be cared for by opening their discharge spouts above the conveyer V, and allowing their contents to be conveyed to the general pile Z. 75 80

Any one of the smaller grades may be loaded directly from its special compartment by letting it flow out through the appropriate spout upon the conveyer V', which will carry the same, as desired, either 85 to the chute K', and car W, at one side, or to the apron conveyer V², and the car X, on the other. Any two grades may be simultaneously shipped from such compartments by likewise allowing a discharge from one 90 compartment to fall on the conveyer V' and be loaded into the car X and, from the other, on the conveyer V to be loaded in the car W.

Stove may be separated and loaded from 95 the general screenings pile Z, by using a 1 $\frac{1}{4}$ inch mesh in the screen H and running the general screenings through the bin B² down said screen to the conveyer V². In this case the resulting screenings will fall 100 into the boot O and be taken up by the elevator and re-sized through the screen U.

In the foregoing instances it is understood, of course, that, when coal is to pass over a screen like H in its travel to a car, a 105 blank or a screen with smaller sized meshes than the coal, will be in place at H.

The above instances are intended to be explanatory and illustrative only of the operation and capabilities of the apparatus in 110 question, and not as defining its limitations.

Other combinations and uses of the same will become manifest on reflection or after some experience in the actual operation of the machine.

Having described said invention what I claim and desire to secure by Letters Patent is:—

1. In a coal handling apparatus the combination of a primary bin, resizing bins, a general screenings bin, and a loading chute with a screening device adapted to receive coal from the primary bin and discharge into the loading chute, means for conveying the screenings from said screening device to a chute, a valve in said chute to direct said screenings into either the general screenings bin or into a resizing screen which latter is adapted to discharge several grades of the coal respectively into resizing bins. 120 125 130

2. In a coal handling apparatus the combination of a primary bin, resizing bins, a general screenings bin, and a loading chute with a screening device adapted to receive 5 coal from the primary bin and discharge into a loading chute, means for conveying the screenings from said screening device to a chute, a valve in said chute to direct said screenings into either the general screenings 10 bin or into a resizing screen which latter is adapted to discharge several grades of coal respectively into the resizing bins, means adapted to receive coal from said general screenings and resizing bins and convey and 15 deliver the same at points below, and means for accordingly drawing off and discharging coal from said bins into said conveying means, substantially as shown and described.

3. In a coal handling apparatus the combination of a primary bin, resizing bins, a general screenings bin, and a loading chute with a screening device adapted to receive coal from the primary bin and discharge into a loading chute, means for conveying 20 the screenings from said screening device to a chute, a valve in said chute to direct said screenings into either the general screenings bin or into a resizing screen which latter is adapted to discharge several grades of coal 25 respectively into the resizing bins, means adapted to receive and convey coal from said general and resizing bins and discharge the same into chutes that lead to loading, screening or storage points below, together with 30 means for severally drawing off and discharging the contents of said last named 35

bins into said last named means for conveying, substantially as shown and described.

4. In a coal handling apparatus, the combination of a primary bin, resizing bins, and a screening device adapted to receive coal from the primary bin, a loading chute adapted to receive the discharge from the screening device, means for elevating the screenings 40 from said screening device, a resizing screen to receive the screenings from said elevating means, which latter is adapted to discharge several grades of the coal respectively into said resizing bins, and a common 45 frame-work for supporting said devices, substantially as shown and described.

5. In a coal handling apparatus, the combination of a primary bin, resizing bins, and a screening device adapted to receive coal 50 from the primary bin and discharge into a loading chute, means for conveying the screenings from said screening device to a resizing screen, which latter is adapted to discharge several grades of the coal respectively 55 into said resizing bins, means adapted to receive coal from said resizing bins and convey and deliver the same at points below, and means for accordingly drawing off and discharging coal from said bins into said 60 conveying means, substantially as shown and described.

WILL K. MONROE.

In presence of—
L. P. LIPPS,
C. S. MALTBIE.
